MICROWAVE VACUUM TUBE

Harold O. Bishop and Donald Kirk, Jr.,
United States Navy

Application June 21, 1946, Serial No. 678,177

7 Claims. (Cl. 250—158)

(Granted under the act of March 3, 1883, as
amended April 30, 1928; 370 O. G. 757)

1

This invention relates to radio vacuum tubes and more specifically is concerned with cathode ray tubes utilized for the generation, amplification, and/or frequency conversion of microwaves.

In the electronic art associated with the utilization of microwaves, frequencies above 1000 megacycles are generated, mixed and amplified. Because the period of such oscillations is one billionth ($\frac{1}{1000000000}$) of a second or less, electron transit-time becomes critically important. All electronic devices utilized in this frequency region must either limit electron paths to a small fraction of the distance they would travel in one half-cycle or utilize electron beams in such a way as to avoid dependence on transit time. In these latter devices, the transit time does not have to be kept to a small fraction of one half-cycle of the operating frequency, which means that their useful frequency range goes to very much higher frequencies.

An object of this invention is to provide a vacuum tube which can function as an amplifier, detector, mixer, or oscillator at frequencies above 1000 megacycles, without limitation due to electron transit time therein; and wherein high deflection sensitivity is achieved through the use of a novel deflection means, resulting in markedly higher tube transconductance for these various tube functions.

In the drawings:

Figure 1 is a schematic view of a typical embodiment of the invention, utilized as an amplifier or as an oscillator.

Figure 2 is a schematic view of a typical embodiment of the invention, utilized as a frequency mixer or converter, such as would be useful in a superheterodyne receiver circuit.

Fig. 3 illustrates a simplified form of part of the apparatus shown in Fig. 2.

Figure 1 shows an arrangement of electrodes within a cathode ray tube. Electron gun 1 provides a beam of electrons 14 which passes through the tube to strike collector plates 10, 10' and 11. Deflector plates 2—2', 3—3', 4—4', 5—5', 6—6', etc., are arranged along the path of said electron beam 14 so as to deflect the beam in a cumulative manner. The voltages developed on said deflector plates are phased by a system of quarter-wave stubs 9 and excited through input loop 7 and connecting line 8. As this arrangement of deflector plates and tuning stubs is excited, the voltage on successive plates varies so as to constantly deflect a given portion of the

2

electron beam in the same direction, as it passes through the tube.

The beam thus deflected from its neutral path can travel from the end of the deflector plate arrangement 10, 10' and 11 through a separation distance that is not critical to the tube's operation. The transit time can be comparatively long without affecting tube operation. When this beam reaches the collector plates the alternate flow to electrode 10 then to electrode 10' causes a current to flow in the shorted quarter-wave line at its resonant frequency. Output loop 13 and its associated coaxial line are shown as a typical method for coupling to the tube to obtain a useful output.

Considering the overall operation of the tube shown in Figure 1, a comparatively weak signal of the proper frequency can be introduced as an input to loop 8. The multiplicity of deflector plates is excited by this input voltage and causes a deflection of the electron beam markedly greater than that which would be caused by a conventional pair of deflector plates. This beam then strikes the collector plates and excites the output circuit 12 so that an amplified signal may be taken off at loop 13. The input 8 may connect to the output 13 through a circuit providing the phase relations necessary for oscillation of the tube and associated circuit.

Figure 2 shows another application of the vacuum tube of this invention in which two sets of deflector plates 15—15' and 16—16' are arranged so as to deflect the electron beam in a single plane. When f_0 and f_s are in phase, additive, the beam is widely deflected and spends most of its cycle striking plates 20 and 20', thus flowing to B+ through connector 22. When f_0 and f_s are 180° out of phase, bucking, the beam is deflected very little and strikes plate 21 most of the time, thus flowing to B+ through connector 23. This change of electron flow from connector 22 to connector 23 and back to connector 22, for every phase change of 360° between incoming signals f_s and f_0 , occurs at the difference frequency, $f_s - f_0$. If circuit 25 is tuned to this difference frequency, a useful output can be obtained.

The tube can be used as a converter instead of a mixer by connecting tuned circuit 26 to leads 20 and 20', and coupling the loop 27 to said tuned circuit 26. The output of loop 27 is then adjusted in phase and applied to deflector plates 15—15' so that the f_0 component in the tube output regenerates the excitation applied to de-

lector plates 16-16', causing oscillation of the tube and circuit at frequency f_0 . As the circuit 26 is tuned to a frequency many times the intermediate frequency, it presents only a negligible impedance to the flow of current at intermediate frequency along connector 22 to tuned circuit 25, so the output as a converter is not appreciably less than the output as a mixer. When connected as a mixer, leads 20 and 20' are connected directly to lead 22 as shown in Fig. 3.

Tuned circuit 26 can be adjusted to resonance at either the input frequency f_s or the local oscillator frequency f_0 for outputs useful in mixers or other circuits requiring amplified voltage at frequency f_s or f_0 , or at their harmonics.

Regarding the internal structure of the microwave vacuum tubes, the separation between the arrangements of deflector plates and of collector plates is not critical. This distance can vary from a very small separation for electrostatic insulation to any convenient distance up to several wavelengths. When the phase relation between input and output must be adjusted to some particular relation, adjustment can be accomplished by varying the voltage B_+ which accelerates the electrons in the beam or by placing a phase adjusting circuit between input and output circuits. Also, deflector plates 15-15' and 16-16' each can be the multiplicity of deflector plates shown in Figure 1, thereby providing a mixer tube of greater sensitivity.

It will be appreciated that the intensity of beam 14 or beam 19 can be varied by adjustment of the potential applied to control grid 28, thereby providing variable gain when used as an amplifier or mixer and providing modulating means when used as an oscillator.

The invention described herein may be manufactured and used by or for the Government of the United States of America for governmental purposes without the payment of any royalties thereon or therefor.

We claim:

1. A device of the character described comprising means for producing an electron beam, means for accelerating said beam, tuned means for deflecting said beam so that a particular portion of the beam is successively deflected in the same direction, and means sensitive to variations in beam deflection for collecting said electron beam.

2. A device of the character described comprising means for producing an electron beam, means for accelerating said electron beam, tuned means for deflecting said electron beam in cumulative impulses as the electron beam is accelerated, a multiplicity of collector plates for said electron beam, and means providing an output in accordance with the deflection of said electron beam as it impinges upon said collector plates.

3. A cathode ray vacuum tube comprising means for producing an electron beam, means for accelerating said electron beam, means for deflecting said electron beam in cumulative impulses of a first frequency, means for deflecting said electron beam in cumulative impulses of a second frequency, and means collecting said elec-

tron beam for providing an output in accordance with the deflection of said electron beam.

4. A cathode ray tube comprising means for producing an electron beam, means for controlling the magnitude of said electron beam, means for accelerating said electron beam, a multiplicity of deflecting plates, tuned connecting means for providing said deflecting plates with voltages so phased as to deflect the electron beam in a cumulative manner, input coupling means connected to said deflecting plates, collector plates for said electron beam, and output coupling means connected to said collector plates.

5. A frequency mixer tube comprising means for producing an electron beam, means for accelerating said electron beam, means for applying a multiplicity of cumulative deflections at a first frequency, means for applying a multiplicity of cumulative deflections at a second frequency, means for collecting said beam after the combined deflection by said first and second frequencies, and output means connected to said collecting means.

6. A cathode ray vacuum tube comprising means for producing an electron beam, means for deflecting a particular portion of said electron beam with a multiplicity of cumulative deflections at a first frequency, means for deflecting a particular portion of said electron beam with a multiplicity of cumulative deflections at a second frequency, a multiplicity of collector plates for said electron beam, and means connected to said collector plates for providing output voltages at said first and second frequencies and at their difference frequency.

7. A cathode ray vacuum tube comprising an electron gun, a multiplicity of deflector plates, an input circuit, a multiplicity of tuned lines interconnecting said deflector plates and said input circuit for providing particularly phased voltages at a first frequency on the various deflector plates, a second multiplicity of deflector plates, a second input circuit, a second multiplicity of tuned lines interconnecting said second multiplicity of deflector plates and said second input circuit for the purpose described at a second frequency, a multiplicity of collector plates, an output circuit for said first frequency and said second frequency, and an output circuit for their difference frequency.
